UNITED STATES PATENT OFFICE.

EMIL THEO. PALMENBERG, OF NEW YORK, N. Y.

GARMENT-HANGER.

1,209,482.

Specification of Letters Patent. Patented Dec. 19, 1916.

Application filed December 27, 1915. Serial No. 68,901.

To all whom it may concern:

Be it known that I, EMIL T. PALMENBERG, a citizen of the United States, and a resident of the city of New York, borough of 5 Manhattan, in the county and State of New York, have invented a new and Improved Garment-Hanger, of which the following is a full, clear, and exact description.

The object of the invention is to provide 10 a new and improved garment hanger more especially designed for supporting ladies' waists and similar garments and holding the same against accidental slipping off should the garment be left unbuttoned or 15 open at the time.

In order to accomplish the desired result, use is made of an arched hanger bar having a central supporting means and provided at the top intermediate the ends and the 20 said supporting means with upwardly extending retaining devices for engagement by the garment hung on the hanger bar.

A practical embodiment of the invention is represented in the accompanying drawings forming a part of this specification, in which similar characters of reference indicate corresponding parts in both views.

Figure 1 is a side elevation of the garment hanger; and Fig. 2 is a cross section of the 30 same on the line 2-2 of Fig. 1.

The hanger bar 10 is preferably made of wood, bent into arch shape and provided at the middle with a supporting hook 11 extending upwardly for supporting the garment hanger and the garment held thereon from a suitable support. The top of the bar 10 is provided near the ends thereof with upwardly extending retaining means 12, preferably in the form of rubber buttons, attached to the heads of nails 13 driven into the top of the hanger bar 10 so as to 35 securely fasten the rubber buttons in place on the top of the hanger bar 10.

It will be noticed that by the arrangement described, a suitable retaining means is provided on the top of the arched hanger bar so that the material of the waist or other delicate garment comes in contact with the rubber buttons and thus the garment is

held against sliding off the hanger bar even 50 should the garment be left open or unbuttoned.

The rubber buttons are preferably made hemispherical so as to prevent the garment material from being injured or caught when 55 slipping off the garment from the hanger or when placing the garment in position on the hanger.

The garment hanger shown and described is very simple in construction and can be 60 cheaply manufactured.

Having thus described my invention, I claim as new and desire to secure by Letters Patent:

1. A garment hanger comprising a hanger 65 bar having a continuous arched upper face, a supporting means projecting upwardly from the center thereof, hemispherical rubber buttons projecting upwardly from the upper face of the bar intermediate the center 70 and each end thereof, said buttons adapted to have frictional contact with the material of a garment to aid in retaining in place and to prevent accidental slipping from the hanger.

2. A garment hanger comprising an arched hanger bar, the upper face of which presents an unbroken continuous curve and rounded ends, an upwardly extending supporting hook at the center of the bar, hemispherical rubber buttons secured to the upper face of the bar adjacent each end of said bar, and nails having pointed shanks projecting from the flat lower face of the buttons and their heads embedded in said 80 buttons below the spherical surface thereof whereby said buttons may be secured to the bar and present an unbroken frictional surface to the material of a garment to prevent 85 its slipping therefrom and from the bar.

In testimony whereof I have signed my name to this specification in the presence of two subscribing witnesses.

EMIL THEO. PALMENBERG.
